UNITED STATES PATENT OFFICE.

JOHN W. ELLIS, OF GREAT FALLS, MONTANA, ASSIGNOR OF ONE-FOURTH TO JOSEPH KIRSCHWING, OF GREAT FALLS, MONTANA.

COLLAPSIBLE RECEPTACLE.

1,133,715.

Specification of Letters Patent. Patented Mar. 30, 1915.

Application filed August 29, 1913. Serial No. 787,325.

To all whom it may concern:

Be it known that I, JOHN W. ELLIS, a citizen of the United States, residing at Great Falls, in the county of Cascade and State of Montana, have invented certain new and useful Improvements in Collapsible Receptacles, of which the following is a specification.

My invention relates to collapsible receptacles, such as knockdown barrels, boxes, nose-bags for horses, or the like; and more particularly to joints for the same, where a steam-tight or waterproof joint is desired.

The object of the device is to construct a receptacle that may be easily and cheaply manufactured, will be strong, lasting, may be easily assembled and disassembled, and will have but few parts.

In the drawings forming a part of this specification, and in which like symbols of reference represent corresponding parts in the several views:—Figure 1 is a perspective view of a barrel, with strips forming the joint, attaching to the same; Fig. 2 is a plan view of the same; Fig. 3 a modification, showing a barrel or the like receptacle, made of a solid or cast piece, the enlargements or strips being integral therewith; and Fig. 4 another modification of the device, showing it applied to a straight side.

In the drawing I have illustrated a barrel, consisting of two halves 1 and 2, the same being connected by an interlocking joint formed by a tongue or tenon 8 largest at the tip and a groove 9, corresponding to the tongue by means of which the sections are securely held together. 3 and 4 represent two strips connected to the inside of the barrel by means of nails or the like. Upon the inner side of the two strips are formed channels within which are inserted gaskets 5, consisting of rubber, leather, asbestos, or the like; and upon said gaskets are placed thin metal strips 6, preferably 45 semicircular in form. Between the metal strips is driven a metallic or other pin 7, so that the parts are forced outwardly and a perfect seal is the result. The gaskets, metal strips, and pins, run, preferably the 50 full length of the joint so as to make what is equivalent to a hermetic seal. The gaskets are shown connected in the present instance by means of pins 13; but of course

they may be otherwise connected, or simply laid in the grooves, the same depending upon the material employed.

In the modification illustrated in Fig. 3, instead of strips 3 and 4 being attached to the receptacle, I have shown them as formed integral therewith, and being merely a swelled or enlarged portion of the receptacle.

In the modification shown in Fig. 4 I have illustrated a joint with the connecting means at both sides of the joint, with forcing pin 7 in the center of the same. This form is more particularly applicable to boats, or where a straight side is used.

Of course it will be understood that my invention is applicable to wooden, metal, or other receptacles, and that the tenons and grooves may be cut or cast in the same in the manufacture of the article as may also the strips or enlarged portions instead of being nailed or otherwise connected as illustrated in the case of the barrel. It will also appear that I may form the article of any number of sections instead of two as illustrated in the drawings.

The construction and use of the device will be apparent from the foregoing description. The sections are first connected by sliding the tongue 8 in the groove 9, the gaskets connected within the recesses or channels, the metallic strips inserted, and the pin driven between the same spreading the parts and making an air-tight joint.

Having now fully described my invention, what I claim as new, and desire to secure by Letters-Patent, is:—

1. A collapsible receptacle, comprising sections having tenons largest at their tips and corresponding grooves formed on the opposing edges of the sections to enable one to take into the other, secondary grooves formed on the opposing faces of the sections, and a pin in the secondary grooves.

2. A collapsible receptacle, comprising sections having tongues largest at their tips and corresponding grooves on the edges of the contiguous sections, and a pin to force the sections in opposite directions.

3. A collapsible receptacle, consisting of sections having their edges connected by tenons having enlarged ends and corresponding grooves, enlarged portions on the

sections formed with grooves, gaskets in the latter grooves, and a pin operating upon the gaskets to force the sections outwardly.

4. A collapsible receptacle, consisting of 5 sections formed with tongues having enlarged tips and corresponding grooves to connect them together, grooved enlargements on the sections, gaskets for the grooved enlargements, metallic strips on the

gaskets, and means to take into the grooves in the enlargements to expand the sections.

In testimony whereof I affix my signature in presence of two witnesses.

JOHN W. ELLIS.
